UNITED STATES PATENT OFFICE.

WILLIAM SANFORD HUTCHINSON, OF OYSTER BAY, NEW YORK.

DRUM-BRAKE.

1,310,992.

Specification of Letters Patent. Patented July 22, 1919.

Application filed January 31, 1917. Serial No. 145,573.

To all whom it may concern:

Be it known that I, WILLIAM S. HUTCHINSON, a citizen of the United States, and a resident of Oyster Bay, Nassau county, New York, have invented a new and useful Improvement in Drum-Brakes, of which the following is a full, clear, and exact description.

My invention relates to improvements in drum brakes such as are generally used on automobiles, although the invention can be applied to any brake which is used on the inner side of a rotary drum to check or stop the drum from rotation. The object of my invention is to produce a simple and powerful brake of this character which will operate without reference to the direction of the rotation of the drum, and more especially to provide a simple, strong and efficient means by which all parts of the shoe will be brought simultaneously to bear on the inner surface of the drum. The invention is especially applicable to the type of brake in which a band is dragged endwise by the frictional contact between the band and the brake drum, and I utilize the drag of the brake shoe to actuate the parts which move all portions of the shoe into simultaneous and firm contact with the drum. By practical experiments on automobiles I have found that where brakes of this character are applied to the inner side of the drum and allowed to come into frictional contact gradually along their length, that is to say where there is a dragging action and the brake shoe takes hold first at one end, the parts wear unevenly, and after a time this unevenness is accentuated so that the brake shoe does not operate so quickly and with such reliability as is desirable. In this style of brake, the setting mechanism simply provides for throwing the shoe into contact with the brake drum, and then the movement of the drum causes the shoe, by reason of certain mechanism which is not here necessary to define, to come into forcible contact with the drum and so stop or check the latter.

In my present invention I connect all the sets of mechanism which serve to force the shoe against the drum in such a manner that all work together simultaneously, and so all parts of the shoe are forced with equal pressure against the drum, thus insuring quick and positive action, and further make it certain that all parts of the shoe wear equally. This will be clearly understood from the description which follows.

Reference is to be had to the accompanying drawings forming a part of this specification, in which similar reference characters indicate corresponding parts in all the views.

Figure 1 is a broken sectional elevation of my improved brake mechanism taken on the line 1—1 of Fig. 2.

Fig. 2 is a broken section on the line 2—2 of Fig. 1.

Fig. 3 is a detail elevation of the support and guide for the shoe.

Fig. 4 is a side elevation of the connector for connecting the several shoe pressure devices.

Fig. 5 is a cross section on the line 5—5 of Fig. 6 of one of the pressure rollers.

Fig. 6 is a side elevation of one of the said rollers.

Fig. 7 is a cross section on the line 7—7 of Fig. 6.

Fig. 8 is a detail section of a part of the shoe showing its relation to its support.

Fig. 9 is a detail view at right angles to that shown in Fig. 8, bringing out in elevation the relation of a shoe, its support, and the means for forcing the shoe against the drum.

Fig. 10 is a detail cross section through the shoe and part of its support.

Fig. 11 is a broken detail side elevation of a part of the shoe.

Fig. 12 is a cross section on the line 12—12 of Fig. 11.

Fig. 13 is a broken side elevation of a part of the shoe support.

Fig. 14 is a cross section on the line 14—14 of Fig. 13.

Fig. 15 is a broken side elevation of a portion of a connector and its means of connection with the shoe.

Fig. 16 is a cross section on the line 16—16 of Fig. 15.

Fig. 17 is a broken detail side elevation of an adjustable block for the pressure devices or rollers.

Fig. 18 is a cross section on the line 18 of Fig. 17.

Fig. 19 is a plan or face view of the structure shown in Fig. 17.

Fig. 20 is a detail side elevation showing a means by which as the brake shoe becomes worn, the lost motion can be taken up.

Fig. 21 is a detail cross section of the structure shown in Fig. 20.

Fig. 22 is a broken detail side elevation of a preferred means of uniting the two members of the connector, and

Fig. 23 is a cross section on the line 23—23 of Fig. 22.

The drum 10 as shown is the ordinary brake drum of a car, but as above stated it can be any rotatable drum to which it is desired to affix or connect a brake. As illustrated the drum connects with the hub of one of the wheels, and opposite one side of the drum is a plate or support 11 which is fast to the hollow axle 12, all the above being purely conventional. Within the drum is a support or bracket 13 which may be carried in a stationary manner in any suitable way, but which is shown supported by bolts 15 which pass through the plate or bracket 11, and through holes 16 in the member 13. The member 13 is preferably provided with a transverse strengthening rib 14, and is cut away for a segment as shown at 14^a to provide for the brake setting mechanism. At intervals the outer web of the member 13 is notched as shown at 17 to provide oppositely inclined walls 18 on which moves the roller or pressure member 19 which serves to force the shoe 24 against the drum 10. This roller 19 turns on a shaft flattened at 20, these parts lying in the sockets 21 in the connector 22, thus preventing the shaft from turning, while the outer ends of the shaft carry rollers 23 which bear against the shoe 24. It will be seen that when the drum is moving and the shoe 24 is brought into contact with the drum, the shoe will move endwise and by reason of its connection with the roller 19 which will be more fully described presently, the said roller and the several similar rollers connected therewith will roll upon the inclines 18 and the rollers 23 will force the shoe into firm contact with the drum.

The outer portions of the pressure devices are preferably covered by caps 25 as shown in Fig. 1, these caps being secured to the opposite members 22 which form the connector.

If desired the tracks 18 upon which the rollers 19 run can be adjustable so as to compensate for wear of the brake shoe and drum, as shown in Figs. 17 to 19. Here the tracks are formed on adjustable blocks 36 which have ribs 37 radially arranged and movable in corresponding ways in the stationary support 13, and the blocks 36 are each backed by screws 38 which screw through an adjacent part of the support 13, and thus by adjusting the screws the blocks 36, the tracks 18, and the pressure devices carried thereby can be moved in or out with reference to the drum and shoe. Any convenient means can be used for preventing the screws from unscrewing, as for instance by running pins 39 through slots 40 in the screws and corresponding holes in the member 13. In this connection attention is called to Figs. 20 and 21, where I have shown a means for taking up the slack or lost motion of the shoe 24 when it has become considerably worn. Without limiting myself to the precise means shown, I can use eccentric rollers 41 which have screw shafts 42 threaded into the stationary plate 11, and the rollers are arranged between the shoe 24 and the stationary part 13 behind it. The screw shafts 42 have squared ends 43, and are secured by lock nuts 44. It will be seen that by loosening the nuts and turning the shafts, the eccentric 41 may be adjusted so as to hold the shoe 24 the desired distance from the drum 10, when the shoe is in released position.

The connector uniting the pressure members 19 is preferably formed of two similar rings 22, and these are firmly united together as shown in Figs. 15 and 16. Obviously a single member connector could be used, or the parts may be connected in different ways without affecting the invention, as I claim any connection between the members 19 which shall cause them to all move in unison. As shown however, a spacer 27 is placed between the members 22 at some part of their length, and parts 28 corresponding in size to the spacer 27 are placed on the outside of the members 22, while rivets 29 or similar fastenings firmly secure all the parts together. This coupling of the members 22 rides in the space 30 (see Fig. 13) which is cut out of the outer portion or web of the member 13, and sufficient space is left to permit of the necessary movement of the coupling parts 27 and 28. These coupling members have projections 31 which fit in the space 32 (see Fig. 11) between the brackets 33 of the shoe 24. Thus when the shoe is moved lengthwise it will act on the projections or teeth 31 of the coupling and move the connector 22 and the rollers 19, causing these to simultaneously roll upon their inclines 18, while

all the rollers 23 of the several pressure devices will impinge at one time upon the shoe 24 and force the latter into firm contact with the drum 10. A preferred means 5 of uniting the two members 22 of the connector is shown in Figs. 22 and 23, in which a block 45 is provided with a tooth 46 to fit between the brackets 33, and the block is recessed as shown at 47 so as to fit firmly 10 over the two members 22, the several parts being united by rivets 48 or equivalent fastening.

It will be obvious that other means can be substituted for connecting the coupling with 15 the shoe, and the connector with the pressure devices, without affecting the invention, and I do not limit my invention to the means shown, although this is well suited for the purpose. To bring the pressure devices to 20 normal position and also to bring the shoe out of normal position, that is to say out of contact with the drum, I employ springs 34 which are fastened to the sides of the bracket 13 and which connect with pins 35 on the 25 connector 22. These springs have opposite tension so as to move the shoe back without reference to which direction it has been previously moved.

To set the shoe in operation, that is to bring 30 it into frictional contact with the drum, I have shown conventional mechanism which is located in the space 14^a at the ends of the bracket 13. This mechanism comprises a crank 37 and links 38 and 39 connecting the 35 crank with the shoe 24. It will be observed that not much power is required in this mechanism, as when the shoe is once in frictional contact with the drum the latter will by its movement move the shoe along as 40 already described, so that the pressure devices 19 and 23 will force the shoe into firm contact with the drum.

It will be seen that the structure which I 45 have described is applicable to any internal strap brake or similar brake in which the drag of the brake shoe actuates pressure devices to force the shoe into firm contact with the drum, and the structure which I have described while serving primarily as a brake, 50 would also be adapted for use as a clutch in certain forms of machinery, without changing the mechanism to any extent.

Attention is called to the fact that when the shoe wears, adjustment can also be obtained by providing the shafts of the rollers 19 with larger contact rollers.

I claim:

1. The combination with the drum and the internal stationary support, of a shoe 60 between the support and the flange of the drum, a plurality of pressure devices carried by the support behind the drum and adapted to force the shoe against the drum flange, and a connector connecting the several pressure devices whereby the move-

ment of one pressure device is simultaneously transmitted to the others.

2. A structure of the kind described comprising a rotary drum, a shoe within the drum having a limited movement or drag 70 with the drum when in frictional contact therewith, means for bringing the shoe and drum into frictional engagement, pressure devices spaced apart behind the shoe, an operative connection between the several 75 pressure devices whereby the movement of one is transmitted to the others so that all will act in unison, and an operative frictional connection between the pressure devices and the shoe whereby the movement 80 of the shoe with the drum will actuate the pressure devices.

3. A brake of the character described comprising a rotatable drum, a shoe within and concentric with the drum flange, said 85 shoe moving endwise when in frictional contact with the drum, means for moving the shoe into frictional engagement with the drum, independent pressure devices spaced apart within the drum behind the shoe and 90 adapted when the shoe is moved endwise to force it firmly against the drum flange, and a rigid connection between the several pressure devices whereby the outward movement of one is instantly and simultaneously 95 communicated to the others.

4. A brake of the kind described comprising a rotatable member, a shoe arranged concentrically with and in close proximity to said member, said shoe having an endwise 100 movement when in frictional contact with said rotatable member, means for moving the shoe into frictional engagement with said rotary member, pressure devices spaced apart behind the shoe and adapted when 105 the shoe is moved endwise to force it against the member, each pressure device comprising an inclined track and rollers arranged to run upon the track, and a connector rigidly connecting the shafts of the several rollers 110 whereby all will move in unison.

5. A brake of the kind described comprising a rotatable member, a shoe arranged within and in close proximity to the member, said shoe having an endwise movement 115 when in frictional engagement with said rotatable member, means for moving the shoe into frictional contact with the member, a support having inclined walls, said walls being arranged at intervals behind the shoe, rollers adapted to run on said inclined walls and force the shoe against the rotatable member when the shoe is moved endwise, shafts extending through the several rollers and on which the rollers run, 120 and a connector supporting the several shafts whereby the bodily movement of one shaft will be transmitted to the several shafts.

6. In a brake of the kind described the 130

combination with the drum and the shoe behind and in proximity thereto adapted to move longitudinally when in contact with the drum, of a stationary support behind the shoe, blocks movable in and out on the support and provided with oppositely inclined walls on the sides next the shoe, rollers arranged to run on the blocks and

to contact with the shoe, and a screw mechanism for adjusting the blocks with relation to the shoe.

WILLIAM SANFORD HUTCHINSON.
